UNITED STATES PATENT OFFICE.

FRIEDRICH ZIEBARTH, OF FRANKFORT-ON-THE-MAIN, GERMANY.

METHOD OF COMPRESSING WOOD OR OTHER ELASTIC MATERIAL.

1,089,687.

Specification of Letters Patent.

Patented Mar. 10, 1914.

Application filed October 24, 1912. Serial No. 727,539.

To all whom it may concern:

Be it known that I, FRIEDRICH ZIEBARTH, merchant, a subject of the Emperor of Germany, and a resident of Frankfort-on-the-
5 Main, in the Empire of Germany, have invented certain new and useful Improvements in Methods of Compressing Wood or other Elastic Material, of which the following is a specification.

10 When stamping wood, straw and the like materials into boilers there are difficulties in tightly stamping the charge, since on account of its elastic properties the material has always the tendency to expand again and to a
15 certain extent to follow the stamping tool, on its back-stroke. Thus it is not only rendered difficult to press tightly the individual layers of material themselves, but the elastic force of the lower layers which have already
20 been pressed, renders it still more difficult to stamp tightly the higher layers, since the stamping tool does not find the resistance in the lower layers which is necessary sufficiently to deform and to compress the material in the upper layers.

The object of the present invention is to avoid this elastic after-effect of the material, so that in this way it is not only possible to stamp it in more efficiently, but also more
30 material can be introduced into the boilers. Thus large quantities of material can be uniformly boiled in a short time in comparatively small boilers with a small expenditure of work and fuel, so that the economy of
5 working of the boiler installation as well as its daily yield is increased.

The invention consists in causing the stamping in of the material to proceed so rapidly that the material has not sufficient
0 time to expand again and to follow the stamping tool on its return stroke.

According to the invention the material can be stamped into the boiler almost as tightly as if it were unelastic or had been
5 compressed by high pressure.

The process can be carried out to special advantage by means of a machine, for example by a pneumatic stamping tool. In the drawing is shown for example the arrangement of a pneumatic stamping installation.

In the interior of the boiler 7, pneumatic stampers 1 are disposed which are connected by means of hose 2 with a joint distributing-crossing 3, the latter being provided with shut-off cocks 10, 12. Compressed air is introduced in the distributing-crossing from any compressed air-source by a principal hose 8, provided with a cock 9 and passing through the neck of the boiler. A counter-balance 6 is secured at the end of a chain 4 conducted over a fixed pulley 5 and the other end of which is connected with an inlet tube 13, the latter being united with the distributing-crossing, and thus the weight of the parts 2, 3, 8, 10, 12 is balanced in such a manner, that the distributing crossing 3 can be moved easily upwardly, as the height of the filling in the boiling-vessel increases.

In carrying out my invention, it is preferable to have the workmen move the stampers 1 in circular rows; thus the drawing suggests an inner row and an outer row. In some cases, it may not be desirable that each workman attending to one of the pneumatic stampers should be able to shut off the supply of air to such stamper; in this case, the cocks 10, 12, may be omitted, so that the workmen within the boiler will be unable to shut off air from any individual stamper, and thus all stampers will always be in operation at the same time. In this case, the operation of the stampers 1 would be controlled exclusively by the master cock 9, which, being outside the boiler, is not accessible to the men working within the boiler.

The cool air escaping from the pneumatic stampers is beneficial to the men within the boiler, and the refreshing effect of this air will enable the men to perform more work in a given time, enabling the material to be fed into the boiler regularly and at a rapid rate.

By the use of my invention the output or working capacity of plants for the manufacture of cellulose, paper, and the like may be increased considerably without increasing either the size or the number of the existing boilers. The cost of installing and operating the improved stamping arrangement is negligible as compared with the saving in

operating expenses and in fuel, and with the better utilization of the boiler plant.

I claim as my invention:

The herein described method of compressing or stamping wood or other elastic material in boilers or other receptacles, which consists in compressing or stamping the material within the receptacle by blows delivered in such quick succession that the mate-

rial will not have sufficient time to expand 10 and to follow the tool delivering said blows, on its return stroke.

In testimony whereof I affix my signature in presence of two witnesses.

FRIEDRICH ZIEBARTH.
